Specification for Design.

Patented Dec. 5, 1916.

Application filed September 13, 1916. Serial No. 119,987. Term of patent 14 years.

To all whom it may concern:

Be it known that I, THOMAS M. PEPPERDAY, a citizen of the United States, and a resident of New York, borough of Manhattan, in the county of New York and State of New York, have invented a certain new, original, and ornamental Design for a Radiator-Casing for Automobiles, of which the following is a specification.

In the accompanying drawing, Figure 1 is a view in front elevation of an automobile

radiator casing, incorporating my new design; Fig. 2 is an outline view taken on the line 2—2 of Fig. 1.

I claim:

The new, original, and ornamental design for a radiator casing for automobiles, as shown.

THOMAS M. PEPPERDAY.
